DESK LAMP

Fred Mugnai, Chicago, Ill., assignor to Art Specialty Co.,
Chicago, Ill., a corporation of Illinois

Application April 26, 1955, Serial No. 35,678

Term of patent 3½ years

(Cl. D48—20)

Fig. 1 is a side elevational view of a desk lamp showing my new design;

Fig. 2 is a front elevational view thereof; and
Fig. 3 is a top plan view thereof.

I claim:

The ornamental design for a desk lamp, as shown.
